ERASER ATTACHMENT FOR TYPEWRITERS

Frederick William Stout, New York, N. Y.

Application June 24, 1938, Serial No. 215,701

4 Claims. (Cl. 248—206)

This invention relates to new and useful improvements in an eraser attachment for typewriters.

The invention has for an object the construction of an attachment which is characterized by a vacuum rubber cup adapted to be pressed into position upon the side of a typewriter, or desk, or other article of furniture, and automatically to maintain its position thereon. In conjunction with this vacuum rubber cup it is proposed to characterize the attachment by a chain or cord or other similar support, connected with the vacuum cup and with an eraser for holding the eraser so that it is readily accessible for use.

Another object of this invention resides in so constructing the attachment that it may easily be removed from the side of a typewriter or the desk or other furniture, without marring or injuring the parts from which it has been removed.

Another object of the invention is the construction of a device as mentioned which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of an eraser attachment for typewriters constructed according to this invention.

Fig. 2 is a side elevational view of Fig. 1.

Fig. 3 is a fragmentary enlarged sectional view showing specifically the details of the suction cup.

Fig. 4 is a transverse sectional view on the line 4—4 of Fig. 3.

Fig. 5 is a similar view to Fig. 3 but illustrating another form of the invention.

The eraser attachment for typewriters, according to this invention, includes a typewriter eraser 10 supported on a bracket 11. This bracket comprises merely a strand of wire bent at its center 11^a and having its free ends 11^b engaged through the conventional central hole 10^a of the typewriter eraser. The bracket 11 is supported on the end of a chain 12 by a connector 13. This connector is attached to the lower end of the chain and is formed with an opening 13^a through which the bracket 11 extends.

The chain 12 has another connector 13 at its upper end which engages upon a hook 14 supported on a vacuum rubber cup 15. This vac-

uum rubber cup has a concave front side 15^a which may be pressed against a smooth flat surface to expel the air so that the rubber cup maintains its position under the weight of the atmosphere.

The hook 14 is threadedly engaged upon the outer end of a stud 16 which is molded into the rear end portion of the vacuum cup 15. A small air passage 17 extends from the curved surface 15^a through the middle of the rubber cup and 10 through the middle of the stud 16. At one point along the length of the stud there is a radially extending branch passage 17^a which is alignable with a passage 17^b formed radially in the shank portion 5 of the hook 14 in one turned position thereof. 15 The arrangement is such that when the hook 14 is normally tightly engaged on the stud 16 the passages 17^a and 17^b are out of line with each other and so the air connection from the interior of the rubber cup with the atmosphere is incomplete.

The vacuum cup 15 is formed with a radially inclined annular face 15^b. This inclination increases the gripping quality of the suction cup which is especially important when the cup is 25 attached to other surfaces than glass.

The eraser attachment for typewriters is used as follows:

The cup 15 is merely pressed against the side of a typewriter or the side of a desk so that it 30 automatically maintains its position. The eraser 10 may be used whenever required. To remove the attachment it is merely necessary to break away the vacuum cup 15 from the article upon which it is mounted. If the hold is too tight 35 14 may be turned so that the passages 17^a and 17^b align with each other. This immediately releases the vacuum within the cup and the cup may easily be removed from its position.

In Fig. 5 the threaded member 14^{''} is provided with a hexagon flange 14^a for turning same. Member 14^{''} is also threaded on the outside to permit a lock nut 14^b to secure a suitable connector of an eraser holding chain or cord, to be clamped between flange 14^a and lock nut 14^b. 45 In other respects this form of the invention is similar to the previous form and the corresponding parts may be recognized by the corresponding reference numerals.

While I have illustrated and described the preferred embodiments of my invention, it is to be understood that I do not limit myself to the precise constructions herein disclosed and the right is reserved to all changes and modifications 5

coming within the scope of the invention as defined in the appended claims.

Having thus described my invention, what I claim as new, and desire to secure by United States Letters Patent is:

- 5 1. An eraser attachment for typewriters, comprising an eraser, a bracket for releasably supporting said eraser, a chain attached at one end to said bracket, a support member attached on the other end of said chain, a vacuum rubber cup for engagement on a smooth surface, a stud molded into the material of the cup and having a projecting shank upon which said member is mounted, and an air passage extending from the inner face of the vacuum cup through said stud and connecting with a radial passage alignable with a passage in said support member, in a certain turned position thereof.
- 10 2. An eraser attachment for typewriters, comprising an eraser, a chain having said eraser mounted on one end thereof, a vacuum rubber cup mounted on the other end of said chain for engagement upon a smooth surface of said typewriter for maintaining said eraser in position with relation to said typewriter, and means at the point of connection between said chain and said cup for releasing the holding action of said cup when desired, comprising a stud molded into the material of said cup and having a projecting shank portion, a support member rotatively mounted upon said projecting shank and having the end of said chain adjacent said cup mounted thereon, and an air passage extending from the inner face of said cup through said stud into said shank portion and connecting with a radial air passage extending to the exterior of said shank portion, said support member being formed with a radially extending passage alignable with said radial air passage in a certain turned position

15 tion of said support member to permit air to enter the hollow of said cup to release the holding action of said cup.

3. In a device of the class described, a vacuum rubber cup for engagement upon a smooth surface, a stud molded into the material of said cup and having a projecting shank portion, a support member rotatively engaged upon said shank portion, and an air passage extending from the inner face of said cup through said stud into 10 said shank portion and connecting with a radial air passage extending to the exterior of said shank portion, said support member being formed with a radially extending passage alignable with said radial air passage in a certain turned position 15 of said support member to permit air to enter the hollow of said cup to release the holding action of said cup.

4. In a device of the class described, a vacuum rubber cup for engagement upon a smooth surface, a stud molded into the material of said cup and having a projecting shank portion, a support member rotatively engaged upon said shank portion, and an air passage extending from the inner face of said cup through said stud into 20 said shank portion and connecting with a radial air passage extending to the exterior of said shank portion, said support member being formed with a radially extending passage alignable with said radial air passage in a certain turned position of 25 said support member to permit air to enter the hollow of said cup to release the holding action of said cup, said support member being threadedly engaged upon said shank portion for permitting said support member to be rotated upon 30 said shank portion to align said radial air passages.

FREDERICK WILLIAM STOUT.
